UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

POWER-TRANSMITTER.

1,163,980.

Specification of Letters Patent. Patented Dec. 14, 1915.

Application filed February 26, 1915. Serial No. 10,680.

To all whom it may concern:

Be it known that I, ALBERT H. DE VOE, a citizen of the United States, residing at Westfield, in the county of Union and State 5 of New Jersey, have invented certain new and useful Improvements in Power-Transmitters, of which the following is a specification, reference being had therein to the accompanying drawings.

This invention relates to adjustable hangers for power transmitters intended primarily for use in connection with sewing machines for manufacturing purposes, and it has for its object to provide a device in 15 which the hanger and the power-transmitting elements carried thereby may be bodily moved relatively to the supporting bracket when it is desired to tighten or slacken the driving belt connecting the power transmitter with the driving pulley of the motor or other power device.

In the present improvements, the power transmitter elements are carried by a hanger slidingly connected to a supporting bracket 25 secured to the under face of the power-table which receives the machine to be driven by the transmission belt or belts. The hanger is provided with alined apertured bosses loosely fitted upon a shaft forming part of 30 the bracket, and the hanger carries an elbow-lever so arranged that one arm thereof comprises a member of a toggle, its complementary toggle member being an arm pivotally connected to the said bracket shaft. 35 When the elbow- or shifting-lever is thrown in a direction to break the toggle, the hanger is bodily moved to slacken the driving belt, and a reverse movement of the elbow-lever will restore the hanger to its normal position 40 and thus tighten the belt. To prevent vibration or the pull of the belt from gradually acting upon the toggle to break the same during the action of the transmitter, the toggle is thrown slightly past its dead-center 45 until a stop member prevents further movement of the shifting lever. Thus the transmitter may be quickly thrown out of driving position to temporarily slacken the driving belt and thereby avoid any useless wear of 50 the same and unnecessary expenditure of power; and a quick movement of the shifting-lever will instantaneously return the transmitter to its predetermined driving position.

55 The driving position of the transmitter is

determined by an adjustment effected by loosening the set-screw which pivotally connects the toggle link with the bracket-shaft and thereafter moving the hanger and link upon said shaft until the proper position is 60 reached, depending upon the tension under which the belt is to be driven. Thus the working position of the transmitter may be changed at will; and, after moving the shifting-lever to slacken the belt, a reverse movement of the lever will restore the hanger and the transmitter parts carried thereby to their exact predetermined working position.

To adapt the transmitter for driving heavy sewing machines and the like, its driven or 70 transmission wheel is formed with two or more V-shaped grooves to receive round belts which engage the walls of similar grooves in the driven pulley of the machine. By this construction the driving pull upon the belts 75 causes them to grip the pulleys with sufficient force to prevent slipping of the belts when the driving load is suddenly increased—as for example when the feeding elements of 80 a sewing machine cross a heavy welted seam in overall work.

In the drawings, Figure 1 is a front elevation of the improvements and Fig. 2 is a bottom plan view, partly in section of the same. Fig. 3 is a perspective view of the improvements.

The power transmitter comprises the usual driving pulleys 1 and 1*, and a transmission pulley 2, loosely mounted upon a shaft 3 clamped by set-screw *s* within the lower one 90 of two transversely-disposed bearing-apertures formed in the boss 4 of a hanger comprising the arms 5 and 6 and the intermediate transversely-disposed bosses 7 and 7*. The upper aperture of boss 4 and the apertured boss 7 are arranged in alinement to receive a horizontal shaft 8 supported in the depending alined bosses *a* and *b* of a bracket A.

The boss 7* is apertured to receive a short 100 rock-shaft 9 having clamped thereon at one end by means of set-screws 10 a starting lever 11 formed with the usual inclined pressure-controlling face 12 which engages the thimble 13 loosely fitted upon the reduced outer end 3* of the pulley-shaft 3. The starting lever acts through the intermediary of the thimble 13 and a suitable bearing device to move the driving pulley in contact 105 with the conical friction face of the trans- 110

mission pulley. At the opposite end of the rock-shaft 9 is clamped by means of set-screw 14 a brake-arm 15 having a friction face 16 which normally engages the periphery of the transmission pulley 2 but which is retracted against the stress of a spring 17 when the starting lever is depressed, as will be understood without further explanation. A thrust bearing 18 is provided to sustain the lateral pressure exerted upon the transmission pulley by the driving pulley during the transmission of power.

The upper portion of the bracket A is a flat-plate 19 apertured at 20 to receive the screws which secure the bracket to the under face of a power-table. Intermediate the plate 19 and the bosses *a* and *b* is a web which unites the bracket wings 21; and at the base of the plate and merging into these wings are two alined bosses 21^x adapted to receive a guide-rod 22 which at one end is bent downwardly to fit within a socket 6^x formed in the vertical apertured arm 6 of the hanger, the rod being held in position by means of the set screw 23.

It will be seen that the arrangement above described permits the hanger and the transmitter members supported thereby to be bodily moved relatively to the bracket A and the power-table, the hanger sliding upon the supporting shaft 8 for this purpose and the guide-rod 22 serving to hold it in proper position throughout such movement.

35 A shifting lever 24 is employed to move the hanger relatively to its supporting bracket. The lever 24 is an elbow-lever and is fulcrumed by means of the fulcrum-stud 25 upon the boss 4 of the hanger and thus 40 moves bodily with the hanger when it is thrown into and out of normal position. The arm 24^x of the shifting-lever forms one member of a toggle, the complemental toggle member being a link 26 pivotally connected by the pin 27 to arm 24^x and at its opposite end pivoted by means of stud-screw 28 to a sleeve 29 fitted upon the shaft 8 and normally held in fixed relation thereto by means of a clamping screw 30. It will 45 be seen that movement of the lever 24 to the right from the position shown in Fig. 1 will break the toggle and swing link 26 to the right in an arc and, through the pivotal connection of the link with arm 24^x, will 50 carry the hanger to the right, the parts assuming the position shown in Fig. 3. A reverse movement of the shifting-lever 24 will restore the hanger and transmitter parts to their normal and driving positions.

55 60 When it is desired to change the normal driving position of the transmitter elements in order to tighten a belt or to loosen it if it becomes too tight through atmospheric changes, it is necessary merely to loosen the 65 set-screw 30 and then shift the hanger and

toggle to the left or right as the case may be and subsequently tighten the said set-screw. It will be noted from an inspection of Fig. 1 that when the hanger is in normal position the toggle members assume a 70 position slightly below the dead-center of their movement and that the contact of a stop-lug 26^x on the link 26 with the upper face of the arm 24^x of the shifting lever will hold the toggle in such position. In this 75 position of the parts it is impossible for the pull of the driving belt or vibration of the hanger to break the toggle.

It will be understood that various changes may be made in the form and arrangement 80 of the elements herein shown and described without departing from the spirit of the invention. For example the form of the hanger may be modified and means other than the guide-rod 22 may be employed to 85 maintain the transmitter elements in proper relation to the supporting bracket.

Having thus set forth the nature of the invention, what I claim herein is:

1. In power transmission devices, the combination with a supporting bracket, of a hanger, a pulley supported in said hanger, means connecting the bracket and said hanger and permitting the bodily adjustment of the latter, a shifting device operatively connected to said hanger including means for instantly returning the hanger to its predetermined working position.

2. In power transmission devices, the combination with a supporting bracket, of 100 a hanger, driving and transmission pulleys supported in said hanger, a sliding connection between said hanger and the bracket, and a shifting lever adapted to hold the hanger in a fixed working position and 105 freely movable in one direction to instantly retract the hanger from such position and freely movable in the reverse direction to restore the hanger to the said working position.

3. In power transmission devices, the combination with a supporting bracket, of a hanger, driving and transmission pulleys supported in said hanger, a sliding connection between said hanger and the bracket, 115 a toggle having one link connected to the bracket and its second link connected to the hanger whereby the hanger is normally held in working position, and a lever adapted to change the position of the toggle links 120 and thereby move the hanger into and out of working position.

4. In power transmission devices, the combination with a supporting bracket, of a hanger, a pulley supported in said hanger, 125 a sliding connection between the hanger and the bracket, a shifting lever adapted to hold the hanger in a predetermined working position and freely movable in one direction to instantly retract the hanger from such 130

position and freely movable in the reverse direction to restore the hanger to the said working position, and means for changing the working position of the hanger at will.

5 5. In power transmission devices, the combination with a supporting bracket, of a hanger, a pulley supported in said hanger, a sliding connection between the hanger and the bracket, a toggle comprising a link 10 connected to the bracket and a second link connected to the hanger and adapted to hold the hanger in a predetermined working position, a lever adapted to change the relative positions of the toggle links and thereby move the hanger into and out of working position, and means for bodily adjusting the toggle link connected to the hanger to change the working position of the latter.

20 6. In power transmission devices, the combination with a supporting bracket including a fixed shaft, of a hanger slidably mounted upon said shaft, a pulley supported in said hanger, an elbow-lever carried by

said hanger, a sleeve adjustably fitted upon the shaft, a link pivotally connected to said sleeve, a pivotal connection between one arm of the bellcrank-lever and said link, and a stop device adapted to engage said elbow-lever upon its movement to a predetermined position.

25 7. In power transmission devices, the combination with a supporting bracket, of a hanger, means connecting the hanger with said bracket and permitting bodily adjustment of the hanger, a shifting device operatively connected to said hanger, and driving and transmission pulleys supported in said hanger, the transmission pulley being formed with a plurality of V-shaped peripheral grooves to receive round belts.

30 35 In testimony whereof I have signed my name to this specification in the presence of two subscribing witnesses.

ALBERT H. DE VOE.
